UNITED STATES PATENT OFFICE.

JAMES P. FEGAN, OF CAMBRIDGE, MASSACHUSETTS, ASSIGNOR TO GEORGE H. SALLAWAY, OF SOMERVILLE, MASSACHUSETTS.

DESIGN FOR A GRIP-LEVER.

SPECIFICATION forming part of Design No. 25,668, dated June 23, 1896.

Application filed May 18, 1896. Serial No. 592,067. Term of patent 14 years.

To all whom it may concern:

Be it known that I, JAMES P. FEGAN, of Cambridge, in the county of Middlesex and State of Massachusetts, have invented and 5 produced a new and original Design for Grip-Levers, of which the following is a specification, reference being had to the accompanying drawing, forming a part hereof.

In the drawing, the figure is a perspective 10 representation of a lever embodying my design.

The essential feature of my design consists 15 in a bar bifurcated at one end and having a spirally-curved hook at the other end, and an intermediate pair of parallel lugs separated from each other and projecting laterally from the bar.

a represents the bar, having its upper end bifurcated, so as to form two substantially

straight horns *b*, having knobs *c* at their 20 ends. At the other end the bar terminates in a spirally-shaped hook *d*, having a knob *e* at its end, and at about the center of the total length of the lever there are formed two pairs of parallel lugs *f*, projecting laterally 25 from the bar.

I claim—

The design for a grip-lever, substantially as shown and described.

In testimony whereof I have signed my 30 name to this specification, in the presence of two subscribing witnesses, this 12th day of May, A. D. 1896.

JAMES P. FEGAN.

Witnesses:

A. D. HARRISON,
P. W. PEZZETTI.
